UNITED STATES PATENT OFFICE.

PETER W. LAMBERT, OF HOBOKEN, NEW JERSEY.

DESIGN FOR A SATCHEL.

SPECIFICATION forming part of Design No. 14,168, dated August 14, 1883.

Application filed April 12, 1883. Term of patent 7 years.

To all whom it may concern:

Be it known that I, PETER W. LAMBERT, a citizen of the United States, residing at Hoboken, in the county of Hudson and State of New Jersey, have invented and produced a new and original Design for Satchels, of which the following is a specification, reference being had to the accompanying drawing.

This design is especially adapted to that class of satchels which are known as "belt-bags" or "side bags," they being commonly suspended from a waist-belt, both for use and ornament.

The novel feature of my design consists of a series of rectangular openings in one or both sides of the satchel, extending in parallel rows, and of lines of depressions on the edges of such openings alternately crossing each other in pairs.

The accompanying drawing shows one side of a satchel containing my design.

The letter A designates the rectangular openings extending in parallel rows, which in this example are at oblique angles to the edges of the satchel, so that each opening resembles a diamond figure. B are the lines of depressions on the edges of the openings. These lines of depressions alternately cross each other in pairs, as shown.

What I claim as new, and desire to secure by Letters Patent, is—

The design for a satchel having its side provided with the rectangular openings A, and the depressed lines B in the edges of the openings, said lines alternately crossing each other in pairs, substantially as shown and described.

In testimony whereof I have hereunto set my hand and seal in the presence of two subscribing witnesses.
